UNITED STATES PATENT OFFICE.

CHARLES THOMPSON, OF HAMILTON, ONTARIO, CANADA.

DIRECTION SIGNAL FOR AUTOMOBILES.

Application filed March 20, 1922. Serial No. 545,271.

To all whom it may concern:

Be it known that I, CHARLES THOMPSON, a subject of the King of Great Britain, and residing in the city of Hamilton, in the 5 county of Wentworth, in the Province of Ontario, Dominion of Canada, have invented certain new and useful Improvements in Direction Signals for Automobiles, of which the following is a specification.

10 My invention relates to improvements in direction signals for automobiles and the object of the invention is to devise a system of signals which will be positive in operation and which will clearly indicate to persons 15 either in front of or to the rear of the automobile the direction in which the same is about to turn.

My invention consists essentially of a pair 20 of pivotally mounted signal lamps, one being at each side of the automobile, directional indicating marks carried at each side of the lamps, the lamps normally disposed parallel to the length of the car, means whereby the lamps may be simultaneously swung 25 laterally about their pivot points, in the same direction, all as hereinafter more particularly described and illustrated in the accompanying drawings in which;

Fig. 1 is a plan view of a part of the cowl 30 of an automobile showing my invention mounted thereon.

Fig. 2 is an elevational detail showing the 35 method of mounting one of my signal lamps, being shown partly in section.

Fig. 3 is a plan view of a flanged mounting for the lamps.

Fig. 4 is a section on the line 4, 4 of Fig. 3.

Fig. 5 is a section on the line 5, 5 of Fig. 40 1 looking in the direction of the arrow.

Fig. 6 is a section on the line 6, 6 of Fig. 2.

Fig. 7 is a central vertical longitudinal section through one of my signal lamps.

Fig. 8 is a section on the line 8, 8 of Fig. 7.

Fig. 9 is a fragmentary detail showing in elevation the connection between the bell crank lever and the links operating the two 50 signal lamps.

Fig. 10 is a plan view of Fig. 9.

Fig. 11 is a perspective view of the bell crank lever and operating bar connected therewith.

Like characters of reference indicate corresponding parts in the different views.

1 is the automobile body and 2 is the cowl portion thereof.

3 and 3¹ are my signal lamps which comprise the bent frame portion 4, made preferably of sheet metal, and forming the top and bottom of the lamps.

5 are inwardly bent flanges at each side of the frame portion 4 and 6 are longitudinally disposed angle strips secured to the inside 65 of the portion 4 and having the inwardly bent flanges 6¹. The flanges 5 and 6¹ form between them guideways adapted to receive the side glasses 7 of the lamp.

8 is the electric bulb which is mounted in 70 the socket 9 in the usual manner in each lamp.

10 is the rear portion of the lamp which is preferably made of sheet metal having the top and bottom flanges 11 and is secured to 75 the lamp by the bolts 12.

13 are directional indicating arrows formed on the side glasses 7 and point forwardly. These are made so as to be illuminated by the bulb in the lamp and may be 80 formed of a clear portion of the glass, the remainder of the body of the glass being dark and opaque.

14 is a lens mounted in the front end of each lamp.

15 is a depending journal portion carried by each lamp and is provided with the axial orifice 16 through which the electric wires 17 extend.

18 are flanged mountings for the lamps 90 and are secured to the cowl 2 near each side of the automobile by bolts 19 extending through the orifices in the flanges 20 and also through registering orifices in the cowl.

The lower depending portions 21 engage 95 orifices in the cowl and the upwardly extending portions 22 support the lamps.

Each mounting is provided with the axial bearing orifice 23 adapted to receive the journal portion 15.

The journal portion 15 extends below the lower end of the mounting 18 and the clamp

24 engages the lower end of the journal, being rigidly secured thereto by means of the bolts 25 (see Fig. 6).

The clamps 24 are disposed so that the shank portions thereof extend longitudinally and rearwardly of the lamps (see Figs. 1 and 2).

26 are curved arms each having an orifice adjacent to the outer end. These arms are 10 pivotally connected to the clamps 24 by means of the bolts 27 which engage the orifices in the outer end of the arms and orifices 28 formed in the clamps 24.

29 is a depending flanged mounting secured to the under side of the cowl by the bolts 30 and is located centrally of the width of the automobile and approximately in line with the mountings 18.

31 is a threaded axial orifice extending 20 upwardly into the lower end of the mounting 29.

32 is a bell crank lever having the central portion 33 and the upper and lower spaced arms 34 and 35 respectively.

25 The central portion 33 is provided with the axial bearing orifice 36 therethrough and the outer end of the arms 34 and 35 are provided with the orifices 37 and 38 respectively.

30 39 is an operating bar pivotally connected at one end to the arm 35 by means of a bolt 39¹ which extends through the orifice 38 in the arm 35 and through a registering orifice in the bar 39. 40 is a handle grip carried by 35 the free end of the bar 39.

The bell crank lever is pivotally connected to the mounting 29 by the bolt 41 which extends upwardly through the orifice 36 and the inner threaded end of which engages the threaded orifice 31 in the mounting 29.

42 and 42¹ are transversely disposed links connecting the arms 26 and the end of the upper arm 34 of the bell crank lever 32.

The outer ends of the links are threaded 45 and engage correspondingly threaded orifices in the arms 26. The inner ends of the links overlap each other and are disposed above and below the end of the arm 34 of the bell crank lever 32. They are also provided with orifices which register with the orifice 37 in the bell crank lever 32 and the three members are pivotally connected by the bolt 43 which extends through all three orifices. This connection is shown in Figures 9 and 10.

The construction and operation of my device is as follows.

60 The invention is adapted to be fitted to any automobile, the lamps being mounted above the cowl and as near the sides thereof as possible. The portions 15 extend through and below the cowl and the entire operating mechanism is situated under the cowl.

65 Normally the lamps occupy the positions shown in full lines in Figure 1 in which they

point forwardly and the directional arrows 13 also point forwardly.

In order to indicate a turn to the right the handle 40 would be pushed forwardly. This would rotate the bell crank lever 32 in 70 a clockwise direction thus also moving the arm 34 thereof clockwise and reciprocating the links 42 and 42¹ towards the left. This rotates the clamps 24 clockwise and since they are rigidly secured to the journal portions 15, the lamps are moved into the positions indicated in dotted lines at A Fig. 1.

In this position the arrows 13 on the front and rear glasses of the right hand lamp indicate to both front and rear of the car that 80 a turn to the right is to be made.

If a turn to the left is to be made the handle 40 is pulled rearwardly, when the reverse of the above described operations takes place and the lamps are thrown into 85 the positions indicated in dotted lines at B in Fig. 1.

I provide a lens 14 in the front end of each lamp so that ordinarily when in the normal 90 positions pointing directly ahead they will show a bright light ahead and act as ordinary side lamps. Also when stopping at the curb at night if the lamp was turned to that side the front lens would illuminate the side walk or entrance to a house.

95 While I have illustrated a specific embodiment of my invention it is obvious that various modifications could be made in the exact details of construction without departing from the spirit of the invention or the scope of the claim and therefore the forms shown are to be taken as illustrative only and not in a limiting sense.

For instance the shape of my lamp might 100 be considerably altered.

Also the particular system of links shown for oscillating the lamps might be altered or the lamps could be oscillated magnetically.

105 From the foregoing it will be evident that I have devised an improved system of directional signals for automobiles which will be positive in operation and the use of which should be of great benefit to the public at large.

110 What I claim as my invention is:

In a direction signal device for automobiles the combination with the cowl portion of the automobile and a pair of signal lamps located one at each side thereof, of bearing brackets carried by the cowl, depending journal portions carried by each lamp and extending downwardly through said brackets, rearwardly extending arms fixedly carried by the lower ends of the journal portions below the bearing brackets, a bell crank lever, an operating handle connected to one arm of the bell crank, distance links pivotally connected at one end to the rearwardly extending arms, the other 120 125 130

ends of the distance links pivotally connected to the second arm of the bell crank, the bell crank lever being pivotally suspended from the under side of the cowl and adapted

5 to be oscillated by the operating handle for reciprocating the distance links and oscillating the lamps simultaneously in either direction, and directional indicating means carried by each side of the lamps, the lamps

normally disposed longitudinally of the automobile and adapted to extend laterally beyond the automobile when in the swung positions.

CHARLES THOMPSON.
